UNITED STATES PATENT OFFICE.

FREDERICK P. SCHOENHARDT, OF MERIDEN, CONNECTICUT, ASSIGNOR TO EDWARD MILLER & COMPANY, OF MERIDEN, CONNECTICUT, A CORPORATION OF CONNECTICUT.

DESIGN FOR A PANEL FOR LAMP SHADES, DOMES, AND THE LIKE.

44,671.

Specification for Design.

Patented Sept. 16, 1913.

Application filed June 21, 1913. Serial No. 775,144. Term of patent 7 years.

To all whom it may concern:

Be it known that I, FREDERICK P. SCHOENHARDT, a citizen of the United States, residing at Meriden, New Haven county, Connecticut, have invented a new, original, and ornamental Design for a Panel for Lamp Shades, Domes, and the like, of which the following is a specification, reference being had to the accompanying drawings, forming a part thereof.

In the drawing I have shown by a single front view a panel embodying my novel design.

I claim:

The ornamental design for a panel for a lamp shade, dome and the like, as shown.

FREDERICK P. SCHOENHARDT.

Witnesses:

LOUIS W. STADTMILLER,
I. B. MILLER.
